UNITED STATES PATENT OFFICE

CHARLES HARRIS, OF CHICAGO, ILLINOIS

DESIGN FOR A CIGAR LIGHTER OR SIMILAR ARTICLE

Application filed July 15, 1929. Serial No. 32,050. Term of patent 3½ years.

To all whom it may concern:

Be it known that I, CHARLES HARRIS, a citizen of the United States, and a resident of the city of Chicago, in the county of Cook and State of Illinois, have invented a new, original, and ornamental Design for a Cigar Lighter or Similar Article, of which the following is the specification, reference being had to the accompanying drawing, forming a part hereof.

On the drawing:

I claim:

The ornamental design for a "cigar lighter" or similar article, as shown.

CHARLES HARRIS.
